UNITED STATES PATENT OFFICE.

ISIDORE HISLAIRE, OF BRUSSELS, BELGIUM, ASSIGNOR TO UNIVERSAL PRODUCE PRESERVATION COMPANY LTD., OF LONDON, ENGLAND.

APPARATUS FOR STERILIZING FOODS.

No. 880,452.

Specification of Letters Patent.

Patented Feb. 25, 1908.

Application filed February 14, 1906. Serial No. 301,075.

To all whom it may concern:

Be it known that I, ISIDORE HISLAIRE, a subject of the King of Belgium, residing at Brussels, 8 Rue Floris, in the Kingdom of Belgium, have invented new and useful Improvements in Apparatus for Sterilizing Foods.

The present invention relates to a special apparatus for treating rapidly and economically foods and other articles by means of sterilizing vapors or gases which may be produced within the apparatus.

The apparatus is made in such a way as to permit of utilizing again, if desired, the said vapors or gases in order perform a number of treatments with the same vapors or gases and to effect if necessary, a treatment under pressure.

The annexed drawing illustrates a construction of the sterilizing apparatus.

Figure 1 is a perspective view of the apparatus; Fig. 2 is a vertical sectional view.

A casing of wood or metal is divided into two compartments by a horizontal partition *b* provided with perforations *c*. The bottom compartment *d* receives the foods or other articles to be treated; the latter, which are introduced through a tight-closing door *e*, may be placed on a hurdle or screen, or may be suspended. A little heating means *f* of any appropriate form is provided for gasifying a pastil *g* of any suitable antiseptic substance. A perforated slide *h*, having a handle *i*, makes or breaks communication between the bottom compartment and the top compartment *j*. Within the latter is mounted a vertically movable piston *k* with a handle *l*.

By means of stoppers or flaps *m*, communication may be established between compartment *d* and the atmosphere, another similar stopper or flap *n* being provided for compartment *j*.

The apparatus operates as follows: The foods or other products to be sterilized are placed within the bottom compartment, the slide *h* being closed; then gasification of the antiseptic matter *g* is produced by the heating means *f* in such a manner as to fill the whole of the compartment with sterilizing

vapors which impregnate the products all the more as the contact lasts longer. When the impregnation of the products treated is deemed sufficient, communication is established between the upper and lower compartment by pulling the slide *h*, after which the piston *k* is raised, the flaps *m* and *n* having been previously opened. The antiseptic vapors are exhausted from the lower into the upper compartment and replaced by fresh air. Afterwards communication between the two compartments is intercepted and then the sterilized products are withdrawn through door *e*. The antiseptic vapors thus stored up in the top compartment may be utilized again by forcing them into the lower compartment, refilled with other products to be treated.

The apparatus, such as described, may be employed to treat product with sterilizing vapors under a certain pressure. It is only necessary for that to produce the vapors within compartment *d* when communication with compartment *j* is established and piston *k* occupies its highest position. In this way, the two compartments get filled with vapor and, by then lowering the piston, after having previously shut the flaps *m*, said vapor is compressed to the desired pressure. The highest obtainable pressure depends upon the relative bulk of the compartments. The antiseptic to be vaporized or gasified may be of any suitable kind, liquid or solid. The form and arrangement of the compartments may also vary to suit practical requirements.

I declare that what I claim is:

1. An apparatus for treating foods with sterilizing or antiseptic gases comprising a casing, a perforated partition dividing said casing into two chambers, means for generating a gas in one chamber, a piston in the other chamber for drawing the gas from the generating chamber to the piston chamber and for returning it to the generating chamber, and means for opening and closing the perforations in said partition.

2. An apparatus for treating foods with sterilizing or antiseptic gases, consisting of a casing divided into two chambers, said

chambers communicating with each other, means for cutting off the communication, means for generating the gas in one chamber, means for admitting air to said chamber and a reciprocating piston in the other chamber for drawing the gas therefrom into the second chamber and for returning it therefrom to the first chamber.

In testimony whereof I affix my signature in presence of two witnesses.

ISIDORE HISLAIRE.
